UNITED STATES PATENT OFFICE.

HOWARD D. COLMAN, OF ROCKFORD, ILLINOIS, ASSIGNOR TO HOWARD D. COLMAN,
LUTHER L. MILLER, AND HARRY A. SEVERSON, COPARTNERS DOING BUSINESS AS
BARBER-COLMAN COMPANY, OF ROCKFORD, ILLINOIS.

YARN-CARRIER.

1,236,822.

Specification of Letters Patent. Patented Aug. 14, 1917.

Continuation in part of application Serial No. 776,237, filed June 28, 1913, and continuation of application Serial No. 809,797, filed December 31, 1913. This application filed January 26, 1916. Serial No. 74,289.

To all whom it may concern:

Be it known that I, HOWARD D. COLMAN, a citizen of the United States, residing at Rockford, in the county of Winnebago and 5 State of Illinois, have invented certain new and useful Improvements in Yarn-Carriers, of which the following is a specification.

This invention relates to devices upon which yarn may be wound. It is especially 10 adapted to support cross-wound yarn masses, and is particularly designed to receive yarn which is subsequently to be unwound in the creel of a warper.

This application is a continuation of application Serial No. 776,237, filed June 28, 1913 (Patent No. 1,228,410, dated June 5, 1917) and application Serial No. 809,797, filed December 31, 1913.

The accompanying drawing is a longitudinal central sectional view through a yarn-carrier embodying the features of my invention, the carrier being shown as locked in operative position upon a suitable support.

25 In the drawing, *a* indicates a yarn mass wound upon the periphery of a headless cylindrical tubular yarn-carrier 1. Said carrier is formed of two sheet-metal sections 2 and 3 rigidly secured together in a suitable manner. In the present embodiment one end of the section 2 is reduced in diameter to fit rigidly within one end of the section 3. Each of the sections 2 and 3 has an annular end wall 4. In each of the end 30 walls 4 is a central opening defined by an inwardly-extending flange 5. A sleeve 6 extends between and surrounds the flanges 5. The inner end of one of the flanges 5 constitutes an annular locking shoulder 7 adapted for engagement by a latch or locking finger to be hereinafter described. In order to provide sufficient clearance between said latch and the sleeve 6, spacer rings 8 are interposed between the ends of the sleeve 6 and the flanges 5.

While the yarn-carrier 1 may be mounted upon various forms of supports, I have herein shown the carrier as fitting upon a hub 9 which is rotatably mounted upon a pivot 10 fixed to a supporting arm 11. The arm 11 is similar to one of the arms 8 shown in my said application Serial No. 809,797.

In order to prevent yarn from being ac-

cidentally wound around the pivot 10, and from getting between the yarn-carrier 1 and the hub 9, there is fixed upon the end of said hub adjacent to the arm 11 a spool 12 comprising end flanges 13 and 14. The arm 11 and the adjacent end of the yarn-carrier 1 are recessed to receive the spool flanges 13 and 14, respectively, so as to insure that any yarn entering the space between the yarn-carrier and the arm shall be wound upon the spool 12. The spool-receiving recess in the end of the yarn carrier 1 is indicated at 1^a.

The spool flange 14 forms a stop determining the operative position of the yarn-carrier upon the hub. The yarn-carrier is releasably locked in such position by means of a yieldable latch finger 15 projecting through an opening in the hub and adapted to confine one of the flanges 5 between the spool flange 14 and said latch finger. For a description of the construction of said locking device reference may be had to the patent to be issued upon an application Serial No. 74,290, filed of even date herewith.

In use, the operative slips the yarn-carrier 1 upon the hub 9, the latch finger 15 yielding inwardly to permit the flange 5 to pass it and immediately springing up into locking position as soon as the bottom wall of the recess 1^a is in contact with the stop flange 14. It will be seen that said bottom wall constitutes a stop for locating the yarn carrier on the hub 9. When it is desired to remove the yarn-carrier, the operative takes hold of the yarn mass and draws it longitudinally of the hub 9, the latch finger 15 yielding inwardly to permit the locking shoulder 7 to pass as fully explained in said application Serial No. 74,290.

Preferably, the yarn-carrier is of relatively large diameter. The relatively large diameter of the yarn mass resulting from the use of a large-diameter yarn-carrier is advantageous in the unwinding of the yarn in the warper creel, since the increased radius affords the yarn greater leverage in turning the yarn mass and hence the yarn is unwound under less tension.

I claim as my invention:

1. A headless cylindrical sheet-metal yarn carrier of relatively large diameter comprising a peripheral portion, two end walls each

of the end walls being integral with the adjacent part of the peripheral portion, each of said end walls having a central opening bounded by an inturned flange integral with 5 such end wall, and a sleeve extending from the opening in one end wall to the opening in the other end wall and surrounding said flanges.

2. A headless cylindrical sheet-metal yarn 10 carrier comprising a peripheral portion, two end walls, each of the end walls having a central opening, and a sleeve extending from

the opening in one end wall to the opening in the other end wall, one of said end walls having an annular central spool-receiving 15 recess communicating with the central opening of said end wall, the inner end of the inturned flange of the said end wall constituting an annular internal locking shoulder, one of the walls of said spool-receiving 20 recess constituting a stop.

In testimony whereof, I hereunto set my hand.

HOWARD D. COLMAN.
